UNITED STATES PATENT OFFICE.

ALLEN A. RUSSELL AND HARLEY A. RUSSELL, OF INDIANAPOLIS, INDIANA.

PNEUMATIC STACKER.

SPECIFICATION forming part of Letters Patent No. 601,356, dated March 29, 1898.

Application filed July 1, 1897. Serial No. 643,173. (No model.)

To all whom it may concern:

Be it known that we, ALLEN A. RUSSELL and HARLEY A. RUSSELL, citizens of the United States, residing at Indianapolis, in the county 5 of Marion and State of Indiana, have invented a new and useful Pneumatic Stacker, of which the following is a specification.

Our invention relates to improvements in pneumatic straw-stackers.

10 The objects of our invention are to produce, first, an improved telescoping portion for the stacker; second, improved means for changing the angular position of the stacker-tubes; third, an improved hood construction; fourth, 15 improved driving mechanism and means for automatically controlling the oscillation of the stacker-tube; fifth, an improved bearing for the fan-shaft; sixth, improved means for introducing the straw into the fan-casing, 20 and, seventh, to provide various improvements in the details of the construction shown in Letters Patent No. 556,776, issued to A. A. Russell March 24, 1896.

The accompanying drawings illustrate our 25 invention.

Figure 1 is a view in perspective of the entire stacker. Fig. 2 is a central vertical section thereof. Fig. 3 is a detail of the hood-operating means. Fig. 4 is a detail of the 30 fan-shaft bearing. Fig. 5 is a detail of the gear-reversing lever. Fig. 6 is a plan of the adjustable hood. Fig. 7 is an end view thereof. Fig. 8 is a perspective of the adjustable hood.

35 In the drawings, 6 indicates the fan-casing, in which is mounted a fan 7 of the usual form. Leading from casing 6 is a discharge-conduit 8. Mounted at the upper end of conduit 8, and revolvable upon a vertical axis thereover, 40 is a pipe 9, to the lower end of which is secured a gear 10, the said gear being mounted in any suitable bearings. Secured to pipe 9, near the lower end thereof, is a band 11, provided with a pair of extending arms 12. Pivoted to the outer ends of arms 12 at 12" are the outer ends of a similar pair of arms 13, carried by a band 14, which is secured to a pipe 15. The upper end of pipe 9 and the co-operating end of pipe 15 are bent into arcs of 45 50 a circle struck from the pivotal point 12", and pipe 15 telescopes over pipe 9. Secured to band 11 and extending upward therefrom are

two standards 16, between which is mounted a reel 17. Secured to the shaft of reel 17 is a worm-gear 18, which co-operates with a worm 55 19, provided with a hand-wheel 20 or other operating means. For the purpose of swinging pipe 15 around pivot 12" one end of a wire rope 21 is secured to reel 17, the other end being passed over and around a pulley 60 22, carried at the upper side of band 14, and then secured to the upper ends of standards 16. It has heretofore been thought necessary to attach the outer end of the lifting cable or rope at some point near the outer end of the 65 stacker-tube, and in such case a derrick is erected over which the rope is drawn, as shown in the patent mentioned above. In the present construction the derrick is removed and reel 17 is placed near the upper ends of the 70 supporting-standards, so that the direction of pull from the reel to the pulley 22 is at all times substantially in line with the direction of movement, so that the stacker-tube may be easily lifted.

75 Mounted so as to telescope over the outer end of pipe 15 is a pipe 23. It is desirable that these two telescoping pipes be so arranged that when brought together they may occupy a minimum amount of space. For this purpose we secure to the upper side of band 14 one end of a bar 24, the arrangement being such that the inner end of pipe 23 may pass under the bar. Mounted at the outer and inner ends, respectively, of bar 24 are sprocket-wheels 25 and 26, over which is passed an endless chain 27, which is fastened at one point to the inner end of pipe 23. By this means pipe 23 may pass under bar 24 and the inner end thereof may be brought back to the 80 85 90 sprocket-wheel 26, thus providing for a considerable extension of the telescoping parts, at the same time allowing the parts to be so contracted as to occupy a very short space. Sprocket 26 is carried by a shaft 28, supported 95 in suitable bearings in band 14. Secured to the outer end of shaft 28 is a hand-wheel 29, provided on its inner face with a series of teeth 30, which are adapted to co-operate with a similar series of teeth 31, carried by a reel 100 32, which is loosely mounted on the shaft. Reel 32 is normally held in engagement with the hand-wheel 29 by means of a spring 33. For the purpose of deflecting the straw

downward as it issues from the outer end of pipe-section 65, hereinafter described, we provide a hood of the following construction: A portion of the bottom of the outer end of pipe 65 is cut away, and to the outer end of the pipe is secured a hollow spherical segment 34. Pivoted at 34" to segment 34, at the ends thereof, is a similar segment 35. Pivoted to segment 35 is a similar segment 36, and pivoted to segment 36 is a segment 37, any desired number of segments being introduced, so as to form an adjustable elbow of the desired angle. It is preferable that the last segment 37 have secured to it at its outer edge a segment 38, which forms a part thereof. The various pivoted segments are prevented from spreading too far apart by means of a short length of chain which passes from segment 34 to segment 38 and is secured at intermediate points to the intervening segments. In order to maintain the hood in its open position, as shown in Fig. 1, a spring 39 is mounted at each side of the hood, one end of said spring being secured to pipe 65 and the other end secured to segment 37, the arrangement being such that the action of the spring is such as to resist the bringing together of the segments. For the purpose of adjusting the hood a cord 40 is secured at one end to the outer segment of the hood and at the other end is secured to reel 32. Reel 32 is of substantially the same diameter as sprocket 26 and is held normally in engagement with the hand-wheel and shaft which operate said sprocket. The arrangement is such, therefore, that when the pipe 23 is moved in either direction upon pipe 15 the cord 40 is wound upon or unwound from reel 32 at substantially the same rate, so that the length of the stacker-tube may be adjusted without in any manner interfering with the adjustment of the hood.

When it is desired to adjust the hood, the operator separates reel 32 and hand-wheel 29 and then turns the said reel in the desired direction. For the purpose of oscillating the stacker we provide the following mechanism: Gear 10 is supported in suitable bearings carried by a framework which forms a part of or may be attached to a separator of any desired type. Supported in suitable bearings on said framework is a shaft 41, upon which is mounted a worm 42, which is adapted to mesh with gear 10. Secured to one end of shaft 41 is a hand-wheel 43, and mounted upon the opposite end of said shaft and revoluble thereon are two opposed bevel-gears 44 and 45, each of which is provided on its inner face with suitable clutch-teeth. Mounted between gears 44 and 45 is a clutch 46, keyed to the shaft and longitudinally movable thereon and provided with teeth adapted to engage with the clutch-teeth of the gears. Mounted between gears 44 and 45 and intermeshing therewith is a bevel-gear 47, which is secured to one end of a shaft 48. Mounted upon shaft 48 and revoluble thereon is a gear 49, which

may be engaged by a clutch 50, keyed to the shaft. Clutch 50 may be thrown out of engagement with gear 49 by means of a bell-crank lever 51 and rod 52. Gear 49 may be driven by any suitable means, such as worm 53 and pulley 54. Pivoted to the framework is a lever 55, arm 56 of which is adapted to engage clutch 46 and shift the same along shaft 41. Arm 57 of lever 55 projects over gear 10 in position to be engaged upon either side by one or the other of a pair of pins 58, which may be placed in any one of a series of holes 58', formed in gear 10, the arrangement being such that as the gear 10 is rotated in either direction by the train of gears just described one of pins 58 will come into engagement with arm 57 of lever 55 and will swing the said lever upon its pivot and shift clutch 46, thus reversing the direction of movement of worm 42 and gear 10. As gear 10 is moved in the reverse direction the other pin 58 is brought into engagement with arm 57 and the direction of movement of the gear is again reversed. The angle of swing of gear 10 and the stacker-tubes carried thereby may be regulated by changing the positions of pins 58. In order to maintain clutch 46 in engagement with either one of gears 44 and 45 and 95 in order to throw the said clutch quickly out of engagement with one gear and into engagement with the other, arm 56 of lever 55 is provided with a forked end 59, which straddles the clutch and lies between a pair of collars 100 which are sufficiently separated to allow the forked end 59 considerable longitudinal play. Mounted upon arm 57 of lever 55 and longitudinally movable in suitable bearings thereon is a catch 60, provided with a V-shaped head 61, adapted to engage a stationary pin 62. Catch 60 is yieldingly held in its normal position by means of a spring 63.

In operation when one of pins 58 comes into engagement with arm 57 of lever 55 the lever is swung upon its pivot, the forked end 59 of arm 56 thereof swinging freely between the collars of clutch 46. This movement of the lever forces the V-shaped head of catch 60 against pin 62 and thus forces the catch 115 backward against the action of spring 63. As soon as head 61 passes the center of pin 62 spring 63 forces the said head forward, thus quickly bringing fork 59 into engagement with one of the collars of clutch 46 and shifting the said clutch along the shaft out of engagement with one and into engagement with the other of gears 44 and 45.

It has heretofore been customary to place in the blast-fan casing a spreading-cone, which operates to spread the straw after it has entered the casing. The great difficulty has been to make the fan, the fan-casing, and the eye of the casing of such proportions that the straw would be properly removed from the casing with as small an expenditure of power as possible. If the eye of the casing is made sufficiently large to easily admit all of the straw, then in order to create sufficient

draft the fan must be so large as to consume a large amount of power. In the present construction we place the spreading-cone 64 in the eye of the casing, but outside of the casing, the bottom of the cone being substantially in line with the top of the casing. By this means the eye of the casing is diminished in size; but the straw is separated and spread just at the point of entrance into the casing, so that it easily enters into the eye and may be quickly disposed of by the fan. The cone may be supported upon the upper end of the fan-shaft, as shown in the drawings, or in any other desirable manner.

In order to support the fan-shaft, we mount the lower end of said shaft within a socket or bearing 66, in the bottom of which is placed a disk or hardened bearing-plate 67. Between plate 67 and the end of the shaft is placed a series of balls 68. In order to adjust the bearing and to regulate the position of the fan within the casing, a set-screw 69 is placed to engage the lower face of plate 67 and to support said plate at any desired point within the socket.

It is often desirable to be able to throw the threshed straw into a barn or mow. With the ordinary construction, in which the hood is mounted directly upon the outer end of the pipe 23, such disposition of the straw is practically impossible. We therefore mount upon the outer end of pipe 23 a short section of pipe 65, which may be rotated upon pipe 23, the section 65 being held in longitudinal position by means of bolts 70, which are secured to pipe 23 and passed through circumferential slots 71, formed through section 65 near the inner end thereof. Secured to the outer end of section 65, in the manner already described, is the adjustable hood, consisting of the various segments 34 to 38, inclusive.

Mounted near the outer end of pipe 23 are two pulleys 72 and 73, over which are passed cords 74 74, the outer ends of said cords being secured to a bolt 75, mounted on the under side of section 65. The opposite ends of cords

74 are allowed to hang within easy reach of the ground, so that by pulling upon one or the other of said cords the section 65, together with the hood which it carries, may be swung from side to side around pipe 23 as an axis, thus making it possible to throw the straw to either side of the machine. By this means the end of the stacker-tube may be introduced through the door of a barn and the straw easily delivered into any part thereof.

We claim as our invention—

1. In a pneumatic stacker, the combination with a pair of telescoping tubes, of a band secured to each tube, an arm carried by each band, the two arms being pivoted together, a standard carried by one of the bands, a reel carried by the standard, means for operating the reel, a pulley carried by the other band, and a cord secured at one end to the reel, passed around the pulley, and secured at the other end to the standard, substantially as and for the purpose set forth.

2. In a pneumatic stacker, a hood for the outer end of the tube thereof, the said hood consisting of a series of hollow spherical segments each of said segments being pivoted at each end to the adjacent ends of the preceding segment only, and a spring, the ends of which are secured to the outer segments the arrangement being such that said spring will tend to spread or separate the segments.

3. In a pneumatic stacker, the combination with the fan-casing thereof, of a spreading-cone mounted in the eye thereof, the said cone projecting above the casing.

4. In a pneumatic stacker, the combination with the fan-casing thereof, of a spreading-cone mounted in the eye thereof, said cone projecting from the casing and the bottom thereof being substantially in line with the top of the casing.

ALLEN A. RUSSELL.
